(57) **CLAIM**

The ornamental design for a lighter, as shown and described.

DESCRIPTION

FIG. 1 is a perspective view of a lighter showing my new design with the switch in a retracted position;

FIG. 2 is a left side elevational view thereof, the right side elevational view being a mirror image thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a perspective view thereof showing the lighter in an open position, and

FIG. 8 is a left side elevational view thereof, showing the switch in an upward position; and,

FIG. 9 is a right side elevational view showing the switch in a depressed position.

The portions shown in broken lines are included for illustrative purpose only and form no part of the claimed design.
